UNITED STATES PATENT OFFICE.

GENEVA KAHN, OF KIRKSVILLE, MISSOURI.

DESIGN FOR A COMBINED PIN AND HAIRPIN HOLDER.

61,307.

Specification for Design.

Patented Aug. 1, 1922.

Application filed October 20, 1921. Serial No. 509,189. Term of patent 3½ years.

To all whom it may concern:

Be it known that I, GENEVA KAHN, a citizen of the United States, residing at Kirksville, in the county of Adair and State of Missouri, have invented a new, original, and ornamental Design for Combined Pin and Hairpin Holders, of which the following is a specification, reference being had to the accompanying drawing, forming a part thereof.

I claim:

The ornamental design for a combined pin and hairpin holder substantially as shown.

GENEVA KAHN.
